Currenttools.com Oct. 28, 2022, 518 Convertible Cart, <https://currenttools.com/products/transport-storage-carts/wire-carts/518-convertible-cart/> (Year: 2022).*Primary Examiner — Cynthia Ramirez(74) *Attorney, Agent, or Firm* — Dority & Manning, P.A.(57) **CLAIM**

The ornamental design for a convertible cart, as shown and described.

DESCRIPTION

FIG. 1 is a perspective view of the convertible cart;
FIG. 2 is a perspective view of the convertible cart of FIG. 1 in a converted dolly configuration;
FIG. 3 is a front view of the convertible cart of FIG. 1;
FIG. 4 is a rear view of the convertible cart of FIG. 1;
FIG. 5 is a right side view of the convertible cart of FIG. 1;
FIG. 6 is a left side view of the convertible cart of FIG. 1;
FIG. 7 is a top view of the convertible cart of FIG. 1;
FIG. 8 is a bottom view of the convertible cart of FIG. 1; and,

FIG. 9 is a perspective view of the convertible cart of FIG. 1, particularly illustrating the convertible cart in use transporting a reel.

The broken lines illustrate portions of the convertible cart that form no part of the claimed design. The additional broken lines in FIG. 9 show environment that is not part of the claimed design.

1 Claim, 9 Drawing Sheets(56)
